UNITED STATES PATENT OFFICE.

LAWRENCE H. JUNKEN, OF SCHENECTADY, NEW YORK, ASSIGNOR TO GENERAL ELECTRIC COMPANY, A CORPORATION OF NEW YORK.

THERMIONIC CURRENT TRANSFORMER.

Application filed December 29, 1925. Serial No. 78,229.

My invention relates to apparatus for obtaining a transformation of current either direct or alternating of any frequency and voltage. My invention is applicable for use as an instrument current transformer and has certain advantages over the ordinary type of instrument current transformer.

In carrying my invention into effect I make use of an electron discharge device and preferably of such a device known in the art as a magnetron. The output current of a magnetron tube is very sensitive to changes in the magnetic field threading the tube and I make use of this characteristic to provide a thermionic current transformer by placing the tube within the influence of the natural magnetic field which is set up around a conductor due to a current flowing therein. The apparatus is so adjusted that the plate current varies with the current in the adjacent conductor and the change in the plate current due to the current flowing in the adjacent conductor may be calibrated and measured or used to operate relays and other devices in the usual way.

For a better understanding of my invention reference is made in the following description to the accompanying drawing, Fig. 1 of which shows the arrangement of the apparatus when used as an alternating current transformer; Fig. 2 is a curve illustrating the characteristics of the apparatus of Fig. 1; and Fig. 3 illustrates the characteristics of the apparatus as adjusted for a different operating condition.

Referring to Fig. 1, 10 represents an electric conductor insulated or otherwise and for the purpose of explaining my invention it will be assumed to be a high voltage alternating current power cable. When current flows in such a cable a concentric magnetic field, sometimes called the magnetic whirl, is set up around the cable as represented by the lines 11. This magnetic field is proportional to the current and if the current is alternating the field reverses with the current. 12 represents a magnetron tube having its axis placed at right angles to the conductor 10 at one side thereof and within the influence of the field 11 thereof. The magnetron tube consists of a sealed glass container which is highly evacuated and contains an axial filament or cathode 13 and a cylindrical anode 14 concentrically arranged with respect to the filament 13 and

the walls of the tube. About the tube is a solenoid 15 for the purpose of producing a basic magnetic field in the tube parallel to its axis. The filament is heated from a battery 16 and between the filament and anode 13 is connected the external circuit containing the battery 17, the primary of a transformer 18, and an adjustable resistance 19. A battery 20 connected in circuit with an adjustable resistance 21 is provided to supply the coil 15 with an adjustable current. The secondary circuit of the transformer contains a translating device 22, such as an ammeter or relay.

As more fully explained in the Physical Review No. 3, September, 1923, pages 279 to 292, the characteristics of the magnetron tube are such that the strength of the magnetic field threading the tube parallel to the axis controls the number of electrons which flow from the filament to the anode under certain conditions. Thus with no field in the tube the electrons are free to flow to the anode unimpeded in an amount depending upon the voltage thereacross and to some extent upon the temperature of the filament. These factors are maintained constant and consequently do not affect the result. As the field strength is increased a point is reached where some of the electrons given out by the filament do not reach the anode and the current in the external circuit starts to decrease. These results are plotted in Fig. 2 where the ordinates represent current in the external circuit and the abscissa represents the field strength. Thus with zero field the plate current is OI' and does not start to decrease until the field has reached a value OF' . Upon a further increase in field the current decreases proportionately and reaches substantially zero at a field strength represented by OF'' . Thus between the values of field strength represented by F' and F'' the tube is very sensitive to changes in field strength, the output current being inversely proportional thereto. I make use of this range of the device in practicing my invention.

The strength of the field produced by coil 15 is adjusted to near the central of this range such as to the value represented by F , which allows a direct current I to flow in the external circuit represented. Now the device is placed adjacent to conductor 10 as represented in Fig. 1 so that the natural flux 110

field of conductor 10 will alternately increase and decrease basic field strength through the tube. The field produced by conductor 10 may be represented as at 23 5 considering the dotted line 24 as a zero flux line. This alternating field is superimposed on the field produced by coil 15 and consequently alternately increases and decreases the current in the external circuit, giving 10 the effect of superimposing an alternating current such as is represented at 25 on the direct current I. The alternating current component thus flowing in the external circuit may be separated out by the transformer 18 so that the current flowing in the device 22 is proportional to that flowing in conductor 10. It will be noted that the ratio 15 of transformation may be easily and minutely varied by moving the tube 12 toward 20 and away from the conductor 10 since the field strength 11 varies inversely with the distance from the conductor 10. The arrangement gives substantial air insulation 25 between the high voltage conductor 10 and the remainder of the system. If desired, other insulating barriers may be provided in place of or in addition to the air insulation.

If we increase the flux produced by coil 15 to the point represented by the field strength 30 F'' in Fig. 3, the basic current flowing in the external circuit is reduced substantially to zero so that the current produced by an additional alternating flux, such as the flux 28, will produce only the positive half waves 35 of an alternating current as represented at 27, or, if the additional flux be produced by a direct current flowing in conductor 10 it will be of constant direction, and if opposed to that produced by coil 15 a resulting direct 40 current will flow in the external circuit of tube 12 which will be proportional to that of conductor 10 and may be measured directly by an ammeter in the anode circuit of tube 12 as represented at 28 when the switch 45 29 is thrown to the left. This will generally be the preferable arrangement when measuring very high frequency alternating current or direct current. The apparatus may be used as a potential transformer by making 50 the current in conductor 10 proportional to the voltage to be measured.

It will thus be seen that I have provided 55 transformer apparatus which is applicable for either direct or alternating current circuits of any frequency and voltage, without cutting or otherwise disturbing the circuit. The device takes no energy from the primary circuit other than that which is ordinarily lost in producing the magnetic whirl 60 11. It is easily adjusted for different transformer ratios and involves no insulating problems.

In accordance with the provisions of the 65 patent statutes I have described the principle of operation of my invention together

with the apparatus which I now consider to represent the best embodiment thereof; but I desire to have it understood that the apparatus shown and described is only illustrative and that the invention may be carried out by other means. 70

What I claim as new and desire to secure by Letters Patent of the United States, is,—

1. Thermionic current transforming apparatus comprising a primary power conductor, an electron discharge device having an output circuit the current of which is responsive to changes in flux variations through said device, means for producing a constant flux field through said device, said device being positioned adjacent and to one side of said primary conductor so that at least a portion of the natural flux surrounding said conductor due to current flowing therein is superimposed upon the constant field through said device, and current responsive means associated with the output circuit of said device. 75

2. Thermionic current transforming apparatus comprising a primary power conductor, an electron discharge device having an output circuit, the current of which is responsive to flux variations through said device, means for producing a constant magnetic field through said device, said device being positioned adjacent and to one side of said primary conductor so that at least a portion of the natural flux surrounding said conductor due to current flowing therein is superimposed upon the constant magnetic field of said device in a manner to vary said field in response to variations in the current flowing in said primary conductor, and current responsive means associated with the output circuit of said device responsive only to the current in said circuit which is due to the superimposed portion of the flux through said device. 80

3. A high voltage power cable and means for obtaining a current responsive to the current flowing in said cable comprising a magnetron tube positioned with its axis at right angles to the axis of said cable and on one side thereof within the influence of the magnetic whirl of said cable, an output circuit for said tube, means for producing a constant flux along the axis of said tube of such a strength as to limit the output current of said tube, and current responsive means associated with the output circuit of said tube. 100

4. Thermionic current transforming apparatus comprising a primary power conductor, a magnetron tube having an output circuit, said tube adjacent said conductor and to one side thereof so that current flowing in said conductor will produce a proportionate flux through said tube, and means for producing a constant flux through said tube of such strength as to just reduce the out- 110 115 120 125 130

put current of said tube to substantially zero when no current is flowing in said primary conductor.

5. Thermionic current transforming apparatus comprising a primary power conductor, a magnetron tube having an output circuit, said tube being positioned adjacent said conductor and to one side thereof so that current flowing in said conductor will produce a proportionate flux through said tube, and means for producing a constant flux

through said tube of such strength as just to reduce the output current of said tube approximately to zero when no current is flowing in said primary conductor, the direction 15 of said proportionate flux, when produced by a direct current in the primary conductor, being such as to oppose said constant flux.

In witness whereof, I have hereunto set my hand this 24th day of December, 1925.

LAWRENCE H. JUNKEN.

put current of said tube to substantially zero when no current is flowing in said primary conductor.

5. Thermionic current transforming apparatus comprising a primary power conductor, a magnetron tube having an output circuit, said tube being positioned adjacent said conductor and to one side thereof so that current flowing in said conductor will produce a proportionate flux through said tube, and means for producing a constant flux

through said tube of such strength as just to reduce the output current of said tube approximately to zero when no current is flowing in said primary conductor, the direction 15 of said proportionate flux, when produced by a direct current in the primary conductor, being such as to oppose said constant flux.

In witness whereof, I have hereunto set my hand this 24th day of December, 1925.

LAWRENCE H. JUNKEN.

Certificate of Correction.

Patent No. 1,645,057.

Granted October 11, 1927, to

LAWRENCE H. JUNKEN.

It is hereby certified that error appears in the printed specification of the above-numbered patent requiring correction as follows: Page 2, line 125, claim 4, before the word "adjacent" insert the word *being*; and that the said Letters Patent should be read with this correction therein that the same may conform to the record of the case in the Patent Office.

Signed and sealed this 22d day of November, A. D. 1927.

[SEAL.]
